CHILD'S TRAVELING COMMODE

Jesse D. Barton, Columbia, S. C.

Application June 24, 1935, Serial No. 28,138

1 Claim. (Cl. 4—135)

The invention consists of a small close rectangular box-like wooden stool constructed of plain boards, open at base and having a cross section inside just above the middle forming a rectangular box at the top in which to conceal a small chamber pot. The top is composed of two cross sections, one having the same dimensions as the top of the stool forms the seat, the other slightly larger in dimensions forms the lid. A small leather strap attached to opposite sides of the stool near the top and passing through small slots on opposite sides of the lid forms a handle for carrying, a brace for the lid when raised and a brace for the lid and seat when lifted.

15 The objects of the invention are, first, to provide a private convenience for regular and emergency eliminations on the part of small children while traveling by automobile; second, to provide a device that makes stops in the thick of traffic 20 and in all kinds of weather unnecessary; and third, to provide a necessary means to avoid exposing small children to unsanitary conditions of public toilets while traveling.

25 My invention is illustrated in the accompanying drawings. Figure 1, Figure 2 and Figure 3 are plan views or working drawings with lid raised. Figure 1 is a vertical front end view, Figure 2 a vertical side view and Figure 3 a top view showing the seat. Figure 4 is an isometric view with 30 lid closed showing leather strap 5, in position for carrying and Figure 5 is an isometric view showing lid and seat lifted for removal and replacement of chamber pot.

The two ends 1—1, and the two sides 11, 11, 35 made of plain boards secured at all connections by water-proof glue, and the cross section 12, a plain board secured on all sides to narrow strip 13, which in turn is secured on all sides to the inside of stool by small screws and water-proof 40 glue constitute the framework of the device.

At base opposite ends are cut square while opposite sides are slightly arched so as to secure a more steady sitting. (See Figures 4 and 5.)

The inside cross section 12, constitutes the bottom of a small rectangular box designed to conceal a small chamber pot 8, with handle fitted into either corner. Cross section 3, a board of the

same dimensions as the top of the stool reenforced on all sides by narrow strip 15, and having in middle egg-shaped opening 9, forms the seat. The seat is secured to one end of stool (the front) by hinges 4, 4, to permit lifting from opposite end for removal and replacement of chamber pot. (See Figure 5.)

Cross section 2, a board slightly larger in dimensions than the seat and reenforced on all sides by narrow strip 15, forms the lid. The lid is secured to top of seat opposite front by hinges 10, 14, so as to permit raising from front for use as in Figure 2. Rubber stop 10, 10, under lid at front with hinges 14, 14, at back maintain space for necessary ventilation over the seat and prevent rattling when lid is closed.

The lid when raised is braced by leather strap 5, passing through slots 16, 16, on opposite sides of lid with ends loosely attached to brass ring 6, on opposite sides of stool. Ring 6, is 20 doubly secured to opposite sides of stool with two short sections of strap 5, attached at two points by screws with counter-sink washers 7, 7. Strap 5, in conjunction with ring 6, serves a triple purpose, first, to brace the lid when raised as in Figure 2; second, to brace the lid and seat when lifted for removal and replacement of pot as in Figure 5; and third, to serve as a handle for carrying as in Figure 4.

I claim:

A traveling commode comprising a box-like stool open at its bottom, a vessel supporting section arranged transversely within the stool forming a concealed box open at its top, two reenforced sections comprising a folding closure, one 35 a toilet seat section having the same dimensions as the top of the stool hinged to said top at the front side, the other a lid section slightly larger in dimensions hinged to the seat at the opposite side, a triple purpose flexible strap passing through 40 slots medially disposed on opposite sides of the lid and means including a ring and two divergently arranged members secured to the ring and to the upper portion of each side wall of the stool for mounting said strap.

45 JESSE D. BARTON.
